UNITED STATES PATENT OFFICE.

KELLY NEWLAND AND LEO J. MILLER, OF COLUMBUS, OHIO.

VEHICLE HEAD LAMP.

Application filed January 28, 1926. Serial No. 84,503.

This invention relates to improvements in motor vehicle head lights and has for its object the provision of a simple and improved form of head lamp involving a peculiar type of reflector assembly by which the light source is concealed from an approaching observer and the reflected light directed upon the roadway in a manner utterly devoid of the vagrant, dazzling and blinding rays emitted ordinarily by head lights of the customary construction.

In accordance with the invention there is provided a head lamp reflector comprising a major reflecting area having a cross-sectional configuration approximating that of a conic section and a supplemental reflecting area of substantially parabolic formation in the axial center of which the light source is arranged, the supplemental reflector, however, being disposed to face toward the rear or inside of the lamp so that the light rays may be directed upon the main reflecting surface of the reflector for projection from the lamp and the light source concealed from a front view.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a vertical sectional view taken through a head lamp constructed in accordance with the present invention.

Figure 2 is a front elevation thereof.

Figure 3 is a horizontal sectional view taken on the line 3—3 of Figure 1.

Referring more particularly to the drawing the numeral 1 designates the metallic shell or casing of a vehicle head lamp, the same being provided with the usual open front which is closed normally by a lens 2 carried in connection with a removable ring 3 secured to the casing 1. Arranged within the casing is a reflector designated in its entirety by the numeral 4, the same consisting of a main reflecting surface 5 disposed within the casing 1 after the manner of an ordinary parabolic reflector. In this instance, however, the sur-

face 5 is in the form of an elongated conic section rather than of the true parabola form of common usage.

The reflector 4 is also formed to comprise at the forward portion thereof an upturned shield or mirror reflector 6, which is disposed to face the interior of the lamp and has its longitudinal axis disposed at an acute angle with respect to the longitudinal axis of the casing 1 and the main reflecting surface 5. A source of light 7, usually in the form of an incandescent lamp, is arranged in the principal axis of the shield 6 and light is reflected from said source of light as shown by dotted lines in Figure 1 of the drawing.

It will be observed that by this construction the light source is masked or concealed from exterior view but is capable of directing a powerful and effective light beam from the lamp downwardly upon a roadway to provide for safe and well illuminated vehicle operation but wherein the obnoxious glare, present in the standard form of head lamp has been eliminated. This is also true regardless of the focal position which the source of light 7 bears to the focal center of the shield or mirror reflector 6.

What is claimed is:

In a vehicle head lamp, a casing, a main reflector arranged within said casing, a baffle plate extending upwardly and forwardly from the bottom portion of said reflector and confined within said main reflector, the upper edge of said plate lies substantially in the horizontal axis of said main reflector to provide a light opening between the upper edges of said baffle plate and said main reflector, a second reflector formed integral with said baffle plate and having its reflecting surface facing the interior of said lamp, a source of light in each of said reflectors, the source of light in said main reflector being so positioned therein that it is concealed from view by the secondary reflector, and means for securing the baffle plate to said main reflector.

In testimony whereof we affix our signatures.

KELLY NEWLAND.
LEO J. MILLER.
